UNITED STATES PATENT OFFICE.

CHARLES A. BAILEY, OF CROMWELL, CONNECTICUT.

DESIGN FOR A TOY SAFE.

SPECIFICATION forming part of Design No. 27,527, dated August 17, 1897.

Application filed May 14, 1897. Serial No. 636,571. Term of patent 7 years.

To all whom it may concern:

Be it known that I, CHARLES A. BAILEY, a citizen of the United States, residing at Cromwell, in the county of Middlesex and State of Connecticut, have invented and produced a new and original Design for Toy Safes, of which the following is a specification, reference being had to the accompanying drawings, illustrating the same, in which—

10 Figure 1 is a front elevation of the safe. Fig. 2 is a view of one of the sides, the two sides being designed precisely alike. Fig. 3 is a view of the back, and Fig. 4 is a view of the top, of the safe.

15 This invention has relation to a certain new and original design for toy safes; and it consists in the novel configuration of parts, as hereinafter described, and illustrated in the accompanying drawings.

20 Referring to the drawings, the front or door A of the safe is ornamented with a central dotted ring a and the upper and lower curved leaf-scrolls a' a'' , within which above and below the aforesaid rings are left spaces to receive a description or trade-name that may be used in connection with the bank, while the edges of the door-panel are ornamented on the hinge side by the pillar a^3 and on the three other edges by the ornamental squares

25 a^4 and points a^5 shown. The central movable knob A' at the center of the door is ornamented by the leaves and scallops a^6 a^7 , as shown. A key-opening a^8 is arranged in a suitable position.

30 The right and left sides of the safe are ornamented precisely alike, each side being de-

signed with an upper and lower rectangular panel B B, the sunken face of which is surrounded by a scalloped border b and ornamented with a vine-and-leaf figure b' . Between the upper and lower panels B is a central panel C, ornamented at the center with a raised circular leaf figure c , surrounded by a ring c' , at the sides of which are extensions or points c^2 , each of the four corners of the panel being ornamented with a leaf figure c^3 .

40 The back D of the safe is ornamented with precisely the same design as the sides, as shown in Fig. 3, the edges of the side panels appearing on each side of the ornamented 45 back panel and a slot d for the passage of money into the bank appearing at the top of the back panel.

45 The top E of the safe, as shown in Fig. 4, is ornamented by a central raised circular figure e , surrounded at a suitable distance by a circle of raised points e' , between which and the central figure e are the series of feather or scroll figures e^2 . These figures all rise from the central sunken part of the top panel 50 and are surrounded by circles e^3 within a curved border e^4 , and at the four corners of the panel are inner and outer scrolls e^5 e^6 , as shown.

55 What I claim is—

60 The design for a toy safe substantially as herein shown and described.

65 CHAS. A. BAILEY.
